US00D793798S

(12) **United States Design Patent** (10) Patent No.: **US D793,798 S**
Carpenter et al. (45) Date of Patent: ** Aug. 8, 2017

(54) **MULTICOOKER**

- (71) Applicant: **WHIRLPOOL CORPORATION**,
Benton Harbor, MI (US)
- (72) Inventors: **Christopher L. Carpenter**, Pearisburg,
VA (US); **Christopher A. Gregory**, St.
Joseph, MI (US)
- (73) Assignee: **Whirlpool Corporation**, Benton
Harbor, MI (US)
- (**) Term: **15 Years**
- (21) Appl. No.: **29/588,333**
- (22) Filed: **Dec. 20, 2016**

See application file for complete search history.

FIG. 1 is a front perspective view of the multicooker of the present invention;
FIG. 2 is a rear perspective view of the multicooker of the present invention;
FIG. 3 is a front elevation view of the multicooker of the present invention;
FIG. 4 is a rear elevation view of the multicooker of the present invention;
FIG. 5 is a left-side elevation view of the multicooker of the present invention;
FIG. 6 is a right-side elevation view of the multicooker of the present invention;
FIG. 7 is a top plan view of the multicooker of the present invention; and,
FIG. 8 is a bottom plan view of the multicooker of the present invention.
The broken lines in the figures are for contextual purposes or show the environment and form no part of the claimed design.
